ATTORNEY

UNITED STATES PATENT OFFICE.

CHARLES WRIGHT, OF FINDLAY, OHIO, ASSIGNOR OF ONE-HALF OF HIS
RIGHT TO YEATMAN BICKHAM, OF SAME PLACE.

STAND-PIPE DRIER FOR SHAFTS.

SPECIFICATION forming part of Letters Patent No. 224,756, dated February 17, 1880.

Application filed January 3, 1880.

To all whom it may concern:

Be it known that I, CHARLES WRIGHT, a citizen of the United States, residing at Findlay, in the county of Hancock and State of Ohio, have invented certain new and useful Improvements in Stand-Pipe Driers for Shafts, &c.; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective view of a device embodying the invention. Fig. 2 is a side elevation of the device. Fig. 3 shows a modification in construction of the device. Fig. 4 is a detail, showing shaft ready to be put on the stand-pipe.

The present invention is designed to afford an easy and convenient means for drying wooden shafts, poles, or any other like device or article after they have been bent into the desired shape or form; and the novelty consists more particularly in the general detail of the construction of the device, all as will now be more fully and in detail set out and explained.

In the accompanying drawings, A denotes a pipe of any desired size and shape, and so adapted and fixed by means of frame or support B as to stand at an incline of any desired angle. Connected to this pipe at each side are the hollow arms a, of which any required number may be used. The arms should have their upper surface rounded. The pipe A may have at its lower end a collar, B', to insure its steadiness, and is connected in any convenient way or manner with a steam or any other heater. The shaft c or other article having been steamed or otherwise dampened, and then bent on a cold form, is fitted over the bent end or heel with a metallic strap,

d, firmly secured thereto, and having the rod 45 e hooked across from the end of the shaft-heel to its body, the said rod forming a chord to the arc made by the bent heel. In this condition the shaft end is so placed upon the arm a that the inside of the curve of the bent heel 50 shall rest upon the rounded upper face of a, while the rod e passes below. When there are several side pipes a and any considerable number of shafts are drying at the same time, their bodies will lap over and rest on each other. The heat radiating from stand-pipe A and its side arms is most advantageously directed to the bent parts, as well as to the bodies of the shafts, &c. This device is easily made and adapted for use, and is very effective, rapid, and thorough in its work.

If desired, the mere shape of the drier can be varied in many ways, as by having a double incline to the pipe A, or by making the drier of gas-pipe, in whole or in part, as is, in a very 65 general way, shown in Fig. 3, and in many other ways and forms.

To insure a free circulation of the heat through the stand-pipe, I may adapt any ordinary or suitable means.

I am aware that heating devices having nozzles or forms for drying hollow articles, such as wearing apparel, have before been used, and therefore do not claim such.

Having thus described my invention, what 75 I consider new, and desire to secure by Letters Patent, is—

The inclined stand-pipe drier A, having hollow arms or lateral extensions a, rounded upon the upper surface, substantially as and 80 for the purposes set forth.

In testimony whereof I affix my signature in presence of two witnesses.

CHARLES WRIGHT.
